J. FEICHTER

RADIATOR CONSTRUCTION

Filed March 13, 1925

Inventor:

John Feichter
By Jones, Addington, Ames & Leibold
G.W.S.

UNITED STATES PATENT OFFICE.

JOHN FEICHTER, OF CHICAGO, ILLINOIS.

RADIATOR CONSTRUCTION.

Application filed March 13, 1925. Serial No. 15,246.

My invention relates to heating systems and more particularly to an improved form of radiator which effectively circulates the heating fluid in a more efficient manner and 5 provides a maximum radiation of the heat therein.

An object of my invention is to provide in a radiator of this type, improved means whereby a continuous circulation, substantially through the entire length of each section, may be more readily obtained, so that this circulation results in a flow of the heating fluid first through one section and then through the adjacent section, alternately, to 15 permit the heating fluid to contact with a maximum radiating surface, the efficiency of the circulation resulting from this continuous movement and maximum contact of the heating fluid.

20 A further object of my invention is to provide an improved structure in the form of an interior partition, which extends lengthwise through each section for dividing the flow and permitting the heating fluid to 25 return on one side to the same pipe comprising the inlet, but which has a two-way flow, such as has been described in my co-pending application, Serial Number 722,233, filed June 25, 1924, this application being a 30 continuation thereof in so far as the common subject matter is concerned.

Other objects and advantages, particularly structural improvements, will be apparent from the following detailed description 35 when taken in connection with the drawings, of which:

Figure 1 is a front elevation of a radiator embodying my invention;

Fig. 2 is a side elevation of the same;

40 Fig. 3 is a vertical sectional view taken on line 3-3 of Fig. 2;

Fig. 4 is a horizontal sectional view of a portion of the various sections of the radiator, this view being taken on line 4-4 of 45 Fig. 3 and looking in the direction of the arrows;

Fig. 5 is a transverse vertical sectional view taken on line 5-5 of Fig. 3; and

50 Fig. 6 illustrates an alternative embodiment of my invention, drawn on a smaller scale.

The difficulties which are met in practice in obtaining maximum heat radiation by the radiators in the usual heating systems employed in the homes and other buildings, due 55 to the fact that the heating fluid is not positively circulated substantially the entire length of each section of the radiator so as to obtain maximum surface contact with the interior walls of the sections, is preferably 60 overcome in accordance with this invention by providing a novel method of connecting the adjacent sections together whereby the heating fluid continuously circulates the entire length of each section, alternately passing 65 from one section to the other, either at the upper or lower ends, and further, by providing improved means whereby the heating fluid is caused to return through the same sections to the inlet pipe preferably 70 having a two-way flow. The sections are furnished with openings at the upper and lower ends and adjacent these openings interengaging flanges serve to interlock adjacent sections, so that the heating fluid 75 when entering the first section preferably rises to the top and passes to the second section where it flows downwardly to the bottom of the same and enters the third section, the circulation continuing in a similar manner 80 until the end section is reached. In the end section, the heating fluid passes to the opposite side where it flows substantially through the entire length of this section, in an opposite direction, and re-enters the next section, so that in effect a return flow 85 through the radiator on the opposite side is obtained. I provide a very simple means for accomplishing this result, being in the form of a partition, secured preferably centrally in each section, and tightly engaging the partition of the adjoining section at the opening where the adjoining section interconnects.

The invention is clearly illustrated in the 95 drawings, in which 10 represents a radiator having a plurality of sections 11, 12, 13, 14 and 15, which obviously may be of any desired type and provided in any number.

By referring to Fig. 3, it will be noted 100 that the heating fluid enters the radiator by way of a pipe 16. A suitable union inter-

connects the pipe 16 at the lower end of section 11. A suitable opening 17 is provided at the lower end of section 11 and an internally threaded flange 18 cooperates with 5 an interconnecting nut 19 which holds a pipe 16 in position at opening 17.

Each section may be provided with openings 17 at their lower ends and with openings 20 at their upper ends. The openings 17 10 and 20 are furnished in a manner on opposite sides permitting the lower openings 17 of adjoining sections to register with each other and the upper openings 20 to likewise register with each other. To hold the sections 15 interlocked, interengaging flanges 21 and 22 may be provided about the openings 17 and 20 to connect the sections alternately at the top and bottom with adjacent sections, this being clearly illustrated in Fig. 3. The 20 inner edge of each section may have a depending web-like portion 24 at the upper and lower ends to serve as reinforcing means, and also as a means to receive a tying rod or bolt 25. Tying rod or bolt 25 functions to 25 interconnect or hold the sections together. The particular type of interengaging flanges 21 and 22 employed may be varied according to the manufacturing problems to be overcome for any desired type of radiator 30 construction. In the drawings, an overlapping type of flange is illustrated, but it will be understood that I do not desire to be limited thereto, but to merely illustrate the same because they facilitate assembly and 35 provide a neat union when the sections are tied together by the rods or bolts 25.

The circulation has been indicated by 40 arrows in Fig. 3. It will be observed that the upper end of section 15 has a transverse opening 16' resulting from the provision of a partitional wall 26 extending between the inner edge and the periphery at the upper 45 end of the section 15. This partitional wall 26 is preferably provided in each of the sections forming the entire radiator, both at the upper and lower ends, that is, the partition runs from the inner edge to the periphery, both at the top and bottom so as in effect to divide each section into two units, 50 this construction being probably more clearly illustrated in the modified showing of Fig. 6.

The circulation then proceeds through the 55 opening 16' to the other side of the last section 15 and again through the entire length of the section, preferably this time in a downward direction and re-enters the preceding section 14. The heating fluid then rises to the top of this section and re-enters 60 the section 13. Thus the heating fluid is returned through the radiator and may leave the same by way of the pipe 16. Pipe 16 may be provided with a dividing wall 28 centrally located so as to register with the

edge of the partition 26 in the lower end of 65 the first section 11.

It will now be evident that according to the teachings of this invention the radiator sections, when placed together and tied by rods 25 will afford a continuous circulation 70 of the heating fluid through the entire length of each section, returning therethrough on the opposite sides of the sections. In other words, the construction is such that a two-way flow is provided through the radiator. 75 This arrangement may be accomplished in any manner desired, but I find that for structural reasons it is advantageous to furnish the partitions 26 in the manner illustrated in the drawings and to alternately 80 arrange the openings 17 and 20 at the lower and upper ends whereby the sections may be interconnected and interlocked to form a complete radiator.

Obviously, the invention is not limited to 85 the specific embodiment illustrated and described herein, but is capable of many variations and other applications within the spirit and scope of the invention as set out by the 90 following claims.

I claim:

1. A radiator construction, the combination of a radiator having a plurality of sections connected together alternately at the top and bottom so that a continuous circulation substantially the entire length of each section is obtained first through one section and then through the adjacent section, and means forming a partitional wall throughout the entire length of each section and also at the union of adjacent sections for providing a similar return circulation through 100 said radiator.

2. A radiator construction, the combination of a radiator having a plurality of sections, said sections each having openings on opposite sides, preferably alternately at the upper and lower ends, so that the heating fluid may enter at one end of each section and flow substantially the entire length to 110 the opposite end, and enter the adjacent section at said opposite end, the heating medium thereby traveling the entire length of each section before passing into the adjacent section, and means for connecting said sections together.

3. A radiator construction, the combination of a radiator having a plurality of sections, said sections each having openings on opposite sides, preferably alternately at the 120 upper and lower ends so that the heating fluid may enter at one end of each section and flow substantially the entire length to the opposite end, means for connecting said sections together to permit a continuous up and down circulation from one section to another substantially throughout the entire 125 radiator, and means for providing a con-

tinuous return circulation through said sections.

4. A radiator, having in combination, a series of sections arranged to provide a continuous circulation of the heating medium from the inlet to the opposite end of the radiator, the heating medium traveling the

entire length of each section before passing into the adjacent section and including means providing a similar return circulation to the inlet end.

In witness whereof, I have hereunto subscribed by name.

JOHN FEICHTER.
